CLAIM

We claim the ornamental design for a mallet finger splint, substantially as shown and described.

DESCRIPTION

FIG. 1 is a frontal view of the new mallet finger splint; FIG. 2 is a rear view of the mallet finger splint shown in FIG. 1.

FIG. 3 is a left end view of the mallet finger splint shown in FIG. 1;

FIG. 4 is a right end view of the mallet finger splint shown in FIG. 1;

FIG. 5 is a top plan view of the mallet finger splint shown in FIG. 1; and,

FIG. 6 is a bottom plan view of the mallet finger splint shown in FIG. 1.

The broken lines in FIGS. 1 and 2 of the drawing are understood to represent stitching. The fragmentary criss-cross pattern shown in these views is understood to be repeated uniformly throughout the areas shown.
